[57] CLAIM

The ornamental design for a hand held shower head and filter housing, as shown and described.

DESCRIPTION

FIG. 1 is a top plan view of a hand held shower head and filter housing shown in FIG. 3;

FIG. 2 is a rear elevational view of FIG. 3;

FIG. 3 is a front elevational view of a first embodiment of my new design of a hand held shower head and filter housing;

FIG. 4 is a side elevational view of FIG. 3, the other side view being a mirror image thereof; and,

FIG. 5 is a bottom plan view of FIG. 3.
